UNITED STATES PATENT OFFICE.

HARRY C. YAEGER, OF POPLAR BLUFF, MISSOURI, ASSIGNEE, BY MESNE ASSIGNMENTS, TO THE DALTON ADDING MACHINE COMPANY, OF CINCINNATI, OHIO, A CORPORATION OF OHIO.

RECORDING-MACHINE.

1,120,878.

Specification of Letters Patent. Patented Dec. 15, 1914.

Application filed September 29, 1913. Serial No. 792,407.

To all whom it may concern:

Be it known that I, HARRY C. YAEGER, a citizen of the United States, residing in the city of Poplar Bluff and State of Missouri, have invented a new and useful Recording-Machine, of which the following is a specification.

This invention relates to recording machines, and has particular reference to mechanism for feeding and adjusting the paper in the paper carriage, and it consists of the novel combination of coöperating devices, and the novel arrangement and mode of operation thereof herein described, and illustrated in the accompanying drawings.

An object of the invention is to provide an improved paper feeding mechanism comprising a revoluble platen, in combination with a plurality of independently supported spring actuated pressure and feed rolls, and means for releasing the pressure of the feed rolls against the platen.

Another object is to provide paper feeding mechanism comprising a revoluble platen in combination with a series of independently supported pressure rolls arranged to coöperate with the platen to feed paper, devices for locating or adjusting the paper between said rolls, means normally holding the pressure rolls in contact with the platen so that they will coöperate with the platen to feed paper and for holding the locating or adjusting devices out of the path of movement of the paper, and means for moving the pressure rolls to position out of contact with the platen and for simultaneously moving the locating or adjusting devices into position to engage the paper.

Another object is to provide paper feeding mechanism comprising a platen, pressure rolls coöoperating with the platen to feed paper, a plate for guiding the paper adjacent to the platen between said rolls, and means for releasing said rolls and moving said paper away from the platen to permit adjustment of the end of the paper between the rolls, in combination with adjusting and locating devices supported between said pressure rolls for receiving and alining or straightening, the ends of the paper being inserted in the machine.

Other objects will appear from the following detail description, reference being made to the accompanying drawings in

which I have illustrated my invention mounted on and combined with an adding and recording machine for purposes of illustration, and in which—

Figure 1 is a side elevation of a "Dalton" adding and recording machine with a part of the paper carriage being in section in order to illustrate essential parts of my invention. Fig. 2 is a sectional view of the paper carriage illustrating the pressure rolls in contact with the platen and also illustrating the lever connections for disengaging the rolls from the platen, said sectional view being taken approximately on the line 2—2 of Fig. 4. Fig. 3 is a sectional view taken approximately on the line 3—3 of Fig. 4 illustrating the pressure rolls disengaged from the platen. Fig. 4 is a front elevation of a part of the paper carriage detached from the machine and illustrates the arrangement of the pressure rolls, and the paper guide plate which serves to guide the paper between the pressure rolls. Fig. 5 is a rear elevation of the paper carriage removed from the machine illustrating the arrangement of the pressure rolls and the paper locating and adjusting devices. Fig. 6 is a sectional view taken on the line 6—7 of Fig. 5 illustrating the pressure rolls in position to coöperate with the platen to feed paper and also illustrating the normal position of the paper locating and adjusting devices out of the path of movement of the paper. Fig. 7 is a similar sectional view on the same section line illustrating the pressure rolls removed from the platen and also illustrating the paper locating and adjusting devices contacting with the platen and in position to receive the forward ends of the paper so that the paper may be readily adjusted and straightened before being passed around the platen.

The platen 1 is supported upon a shaft 2 which is mounted in a paper carriage 3 superimposed and operating upon a suitable carriage support embodied in the machine. The platen shaft is provided with knobs 4 for manual rotation and adjustment.

A shaft 5 is supported in the platen carriage below and parallel with the platen and at suitable intervals is provided with grooves 6. In the grooves 6 the bifurcated ends of the rearwardly extending arms 7 are seated. The arms 7 are arranged in pairs

and each pair of arms supports a pressure roll 8, the series of pressure rolls 8 being axially alined and adapted to coöperate with the platen to serve as the rear pressure rolls in feeding the paper. One part of the space in the fork of each of the arms 7 is somewhat extended as indicated at 9, (Fig. 3) so as to provide a surface for a camming action of the shaft 5 whereby said shaft 5 will depress the rear ends of the arms 7 to carry the rolls 8 out of contact with the platen. The shaft 5 is provided with notches 10, in effect being deeper cuts or depressions of the grooves 6 and being arranged to receive the cam portions 9, thereby permitting the levers 7 to move to press the rolls 8 against the platen. Each of the levers 7 has an extension 11 engaging under a rod 12 in the carriage so that when the shaft 5 is turned to move the notches or depressions 10 away from the cam surfaces 9, and to operate the larger portions of the shaft 5 against said cam surfaces the upper ends of the lever 7 will be depressed and the pressure rolls 8 will be removed from the platen, as illustrated in Fig. 3.

Forwardly extending curved arms 13 are seated in grooves 14 in the shaft 5 and have rear extensions 15 projecting over the rod 12. The grooves 14 are provided with deepened portions 16, similar to the deepened portions 10, normally receiving cam surfaces 17 on the lever 13; similar to the cam surfaces 9 on the levers 7. In the normal position of the shaft 5 the cam and surfaces 17 are seated in the deepened notches 16, just as the cam portions 9 are normally seated in the deepened notches 10. The arms 13 are also arranged in pairs, preferably being one pair of arms 13 for each pair of arms 7, and axially alined pressure rolls 18 are supported between the front ends of said arms 13. Each arm 7, in the embodiment shown, is connected to the corresponding arm 13 by a spring 19, so that normally the rolls 8 and 18 are yieldingly retained in contact with the platen. Obviously, when the shaft 5 is turned to a position such as illustrated in Fig. 3 the rolls 8 and 18 will be moved out of contact with the platen.

A lever 20 (Figs. 2 and 5) is attached to the shaft 5 and is connected by a link 21 with the lower end of a lever 22 which is pivoted upon a support 23 in the carriage. The upper end of the lever 22 is provided with a handle 24 for manual engagement. By operating the lever 22 to the position shown in Fig. 3 the shaft 5 is turned and performs a camming action upon all of the levers 7 and all of the levers 13, thereby depressing the pressure rolls carried by said levers out of contact with the platen and permitting free movement and adjustment of the paper.

65 A paper table 25 is supported in an ob-

lique position in the carriage at the feeding-side of the platen and is arranged to receive and support the paper passing to the platen. A rod 26 is supported in the carriage adjacent to the lower edge of the paper table 25, and a plate 27 has its rear upper edge pivotally engaged upon said rod. The plate 27 constitutes a separately adjustable continuation of the paper table 25 and is curved under the platen concentrically with the platen and with the platen shaft 2, so that the paper passing from the paper table 25 will be received by the plate 27 and thereby guided under the platen and directed to the feeding-out side of the platen. The portion of the plate 27 which is under the platen is yieldingly supported by the springs 19, so that when said springs are retracted to hold the pressure rolls 8 and 18 in contact with the platen, said plate 27 will be held adjacent to the platen, leaving sufficient space, however, for the passage of the paper as illustrated in Figs. 2 and 6. In manifolding, or in passing thick or doubled portions of the paper around the platen the plate 27 will yield to give the necessary room for the paper, by pressing upon and bending the supporting springs 19. Said plate 27 is provided with slots or openings 28 through which the feed rolls extend and operate against the platen. Thus, the plate 27 will yield for manifold work or for doubled or thick portions of the paper without interfering with the free operation of the pressure roll, and vice versa.

At suitable intervals the shaft 5 is provided with grooves 29 (Figs. 6 and 7), which form flat portions on the shaft. A paper stop-arm 30 is mounted upon each of the flat portions formed by the grooves 29, said arms being under control of springs 31 whereby the rear ends of said arms are actuated toward the platen. In the normal position of the shaft 5, that is, when the pressure rolls 8 and 18 are in coöoperative engagement with the platen, the edges of the flat portions formed by the grooves 29 engage against flat parts of the stop-arm 30 and hold the rear ends of said arms depressed and out of contact with the platen and out of the path of movement of the paper, in opposition to the springs 31. When the shaft 5 is rocked, by manipulation of the lever 22, the arms 30 are released from restraint by said shaft 5 and the rear ends of said arms are actuated against the platen, passing through slots 32 provided for that purpose (Figs. 5, 6 and 7). Thus, simultaneously with the release of the pressure rolls the arms 30 are moved into engagement with the platen below the pressure rolls 8 and rearwardly from the pressure rolls 18. The upper ends of the arms 30 are provided with notches or paper seats 33 adapted to receive the front ends 130

of the sheets of paper which are being inserted or passed to the paper feeding mechanism. Thus, in manifolding the sheets of paper may be located in position to be engaged by the paper feeding mechanism, and may be accurately adjusted before being engaged thereby. After the sheets of paper have been accurately located and adjusted the lever 22 is returned to its normal position, as a result of which the pressure rolls 8 engage the accurately adjusted sheets of paper, the arms 30 are moved out of the path of the paper, and the guide plate 27 assumes its proper position to guide the paper under the platen to the rolls 18.

From the foregoing it will be understood that the entire paper control mechanism, including the paper guide plate, pressure rolls, and the devices for positioning and adjusting the paper, are controlled by manipulation of a single lever; so that, as an incident to the release of the pressure rolls, the paper positioning and adjusting devices are moved into position to be engaged by the paper without any special attention by the operator. Also, as the pressure rolls are engaged against the paper, the paper positioning and adjusting devices are automatically moved out of the path of the paper, so that the paper can pass freely under the platen. It will be observed that as a result of the arrangement of the arms 7 and 13 upon the shaft 5, and the arrangement of the arms 30 upon said shaft an important timing of their operations is effected, so that the pressure rolls 8 will engage the paper before the arm 30 are released from the paper. This may be understood by reference to Figs. 2 and 3, and a comparison thereof with Figs. 6 and 7, in which it will be observed that as the shaft 5 is rocked to permit the pressure rolls 8 to engage the paper, the arms 30 are not operated or disengaged from the paper until after the rolls 8 have engaged the paper. Thereupon by a slight further movement of the shaft 5 the arms 30 are disengaged from the paper and are moved out of the path thereof.

A number of modifications may be utilized wherever desired so as to adapt my invention to individual purposes or to different machines, it being understood that I do not restrict myself to the specific arrangement illustrated and described except where set forth in the appended claims.

What I claim and desire to secure by Letters Patent is:

1. In a recording machine, the combination with a revoluble platen, a rock-shaft, arms pivotally supported by said rock-shaft, pressure rolls supported by said arms and arranged to coöperate with the platen to feed paper, cams on said arms whereby said rock-shaft actuates said arms to move said rolls away from said platen, a paper guide

for guiding the paper against the platen, paper stop-arms pivoted upon said rock-shaft and movable into and out of the path of movement of the paper, and cams whereby said rock-shaft moves said last-mentioned arms into the path of movement of the paper when said rolls are moved away from said platen, of a lever operable to actuate said rock-shaft to release said pressure rolls from the platen, and means independent of said first-named arms operable to move said paper stop-arms into the path of movement of the paper, substantially as described.

2. In a recording machine, the combination with a platen, of a shaft, series of arms pivotally supported on said shaft, cams whereby said shaft will move said arms, a second series of arms also pivoted upon said shaft, cams whereby said shaft will actuate said second series of arms, pressure rolls supported by each series of arms, paper stop-arms also pivoted upon said shaft, cams whereby said shaft will actuate said paper stop-arms out of contact with said platen, springs for actuating said pressure rolls into contact with the platen, a lever for operating said shaft to disengage said rolls from said platen, and means independently of said first-named arms acting to engage said paper stop-arms with said platen, substantially as described.

3. In a recording machine, the combination with a platen, of a shaft supported parallel with said platen, series of arms supported upon said shaft, pressure rolls carried by said arms, springs connecting the arms of one series with the arms of another series and actuating said pressure rolls into contact with said platen, a paper guide plate resting upon said springs, and a lever for actuating said shaft and said arms to disengage said rolls from said platen, thereby moving said springs and permitting said paper guide plate to move away from said platen, substantially as specified.

4. In a recording machine, the combination with a platen, of a shaft supported parallel with said platen, a rearward series of arms pivotally supported by said shaft, a forward series of arms pivotally supported by said shaft, pressure rolls carried by each of said series of arms, springs connecting said forward and rearward series of arms and actuating said pressure rolls against said platen, a rod, a paper guide plate pivoted on said rod and resting upon said springs, and a lever for operating said shaft effectively to move said pressure rolls away from said shaft, and to move said springs to enable said paper guide plate to move away from said platen, substantially as described.

5. In a recording machine, the combination with a platen, a shaft adjacent to said

platen, a forward series of arms and a rearward series of arms pivoted on said shaft, pressure rolls carried by each series of said arms, springs connecting said forward series of arms with said rearward series of arms and actuating said pressure rolls against said platen, a rod, a guide plate pivoted on said rod and resting on said springs, and a lever operable to move said rolls away from said platen, and to move said springs to permit said guide plate to move away from said platen, of paper stop-arms pivoted on said shaft, and means for moving said arms into contact with said platen when said lever is operated as aforesaid, substantially as described.

6. In a recording machine, the combination with a platen, of a rock shaft, a fulcrum rod, a forward series of arms pivoted upon said shaft and engaging said rod, a rearward series of arms pivoted upon said shaft and engaging said rod, pressure rolls carried by said forward series of arms at the feeding-out side of the platen, pressure rolls carried by said rearward series of arms at the feeding-in side of the platen, springs connecting said forward series of arms with said rearward series of arms effectively to actuate said pressure rolls into contact with said platen, a cam integral with each of said arms, parts formed on said shaft for engaging said cams to operate said arms, and a lever for rocking said shaft to operate said arms as aforesaid, substantially as described.

7. In a recording machine, the combination with a platen, of a rock shaft, arms pivotally supported by said rock shaft, pressure rolls supported by said arms and arranged to coöperate with said platen in feeding paper, springs actuating said arms to hold said rolls in coöperative relationship with respect to said platen, paper stop-arms pivoted upon said rock shaft, springs actuating said paper stop-arms toward said platen, means for holding said paper stop-arms out of contact with said platen in the normal position of said rock shaft, means for moving all of said first-named arms away from said platen when said shaft is rocked, and means for rocking said shaft to move said first-named arms away from said platen, and to enable said last-named springs to move said paper stop-arms into engagement with said platen, substantially as described.

8. In a recording machine, the combination with a platen, of pressure rolls arranged to coöperate with said platen to feed paper, a plate arranged to coöperate with said platen and said rolls to guide the paper, springs holding said rolls and said plate in position to feed and guide paper, a rock shaft controlling said rolls and said springs, paper stop-arms supported on said rock shaft, means for holding said stop-

arms out of contact with said platen while said rolls are in contact with said platen, means for rocking said shaft effectively to move said rolls out of contact with said platen, and means for engaging said stop-arms with said platen when said shaft is rocked as aforesaid, substantially as described.

9. In a recording machine, the combination with a platen, of a rock shaft, roll-supporting arms pivoted on said shaft, rolls supported by said arms, springs actuating said rolls into contact with said platen, means for rocking said shaft, and means for moving said arms when said shaft is rocked, thereby moving said rolls out of contact with said platen, of paper stop-arms pivoted on said rock shaft, means holding said stop-arms out of contact with said platen when said rolls are in contact with said platen, and means for moving said stop-arms into contact with said platen when said shaft is rocked as aforesaid, substantially as described.

10. In a recording machine, the combination with a platen, of pressure rolls arranged to coöperate with said platen, a rock shaft, arms pivoted on and supported by said rock shaft and supporting said pressure rolls, means for rocking said shaft, means for moving said pressure rolls away from said platen when said shaft is rocked, paper stop-arms pivoted upon said rock shaft, means normally holding said stop-arms out of contact with said platen, and means independent of said first-named arms for moving said stop-arms into contact with said platen when said shaft is rocked as aforesaid, substantially as described.

11. In a recording machine, the combination with a platen, of a rock shaft, roll-supporting arms pivoted on said shaft, rolls supported by said arms, means normally holding said rolls in position to coöperate with said platen to feed paper, paper stop-arms pivoted on said shaft, means normally holding said stop-arms out of contact with said platen, means for actuating said arms by the rocking of said shaft to move said rolls away from said platen, and springs acting independently of said first-named arms for moving said stop-arms into contact with said platen when said shaft is rocked to move said rolls away from said platen, substantially as described.

12. In a recording machine, the combination with a platen, of a rock shaft, arms pivoted on and supported by said rock shaft, pressure rolls supported by said arms and arranged to coöperate with said platen to feed paper, springs connecting certain of said arms with others of said arms effectively to actuate all of said pressure rolls against said platen, paper stop-arms pivoted on said rock shaft, cams whereby said

rock shaft holds said stop-arms out of contact with said platen during the time that said pressure rolls are in contact with said platen, springs for actuating said stop-arms 5 into contact with said platen, a paper guide plate supported in position by said first-named springs, and means for rocking said shaft effectively to move said pressure rolls out of contact with said platen and to enable said second-named springs to move 10

said stop-arms into contact with said platen, substantially as described.

In witness whereof, I have signed this specification in the presence of two subscribing witnesses.
